MULTIPLE TANK FUEL SYSTEM

David Samiran, Osborn, Ohio

Application February 12, 1943, Serial No. 475,683

9 Claims. (Cl. 158—36.4)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to fuel systems and has particular reference to systems employing a plurality of fuel tanks such, for instance, as the system on an aircraft.

An object of the invention is to provide a fuel system of this character with means to maintain the pressure in the fuel line substantially constant while changing the connection of the suction side of the fuel pump from one tank to the next as successive tanks are emptied.

Another object is to provide power-operated means to change the connections of the fuel pump, which extend to the fuel tanks, from an empty to a full tank, with means for automatically sensing the fact of an empty tank and applying the power means for making the change, then disconnecting the power means after the change is made.

Another object is to provide manually selective means for quickly connecting to any one of the several tanks, independently of the power means, when that becomes desirable.

Other objects and advantages will be readily perceived by a study of the following description with reference to the drawings, wherein:

Fig. 1 is a schematic view of a fuel system made according to my invention;

Fig. 2 is an enlarged view of the solenoid-operated valves of Fig. 1 shown in detail;

Fig. 3 is an enlarged vertical axial section through the air eliminator of Fig. 1;

Fig. 4 is an enlarged vertical axial section through a special check valve of Fig. 1;

Fig. 5 is an enlarged vertical section through either the main pump or the auxiliary pump of Fig. 1;

Fig. 6 is an axial section through the power-operated selective switch for operating the solenoid valves.

Similar numerals refer to similar parts throughout the drawings.

Referring now particularly to the schematic illustration Fig. 1, an engine 10 carries a main fuel pump 12, the pump being operatively connected to the engine to be rotated thereby, and adapted to supply fuel to a carburetor 14. A manifold 16 connects the intake side of the fuel pump 12 to a series of tanks 1 to 6, inclusive, the fuel passing through solenoid-operated valves 18 to 23, which control the flow from the tanks to the pump.

2

Referring to Fig. 2, which shows an enlarged longitudinal cross section through one of the solenoid-operated valves, the flow between the inlet 30 and the outlet 32 is controlled by a valve disk 34 which is lifted to "open" position by a solenoid core 36, which is in turn lifted by coils 38 and 40. The coil 38 is wound of relatively coarse wire and few turns, while the coil 40 is wound of finer wire, the intention being to apply a heavy current to the coil 38 to lift the valve disk from its seat, then discontinue the heavy current in the coarse wire coil 38 and apply a small current to the fine wire coil 40, to thereby hold the valve in "open" position with a minimum expenditure of energy. A solenoid-controlled valve, such as is shown in Fig. 2, will be described and claimed in a separate application of which I am joint inventor.

A fuel discharge pipe 42 extends from the main fuel pump 12 to the bottom of an air separator 44, the outlet pipe 46 of which delivers fuel to the carburetor 14. The pump 12 is of the type having a built-in relief valve such as is shown at 57 in the enlarged view, Fig. 5 being thereby adapted to maintain a given pressure output, the relief valve in this pump being adjusted to deliver fuel to the outlet at fifteen pounds pressure. A float 48 in the top of the air separator is so loaded as to permit the discharge of vapor from the top of the separator to the tops of the tanks through a pipe 50 when the amount of accumulated vapor in the top of the air separator forces the liquid fuel down to a predetermined level.

The air separator is unique in that it is arranged to receive the fuel discharged from both the main pump 12 and an auxiliary pump 52 and discharge the fuel free from air through a common pipe 46. It is shown in detail to an enlarged scale in Fig. 3 and comprises an outer vessel 11 and a concentric inner vessel 13 secured together so as to leave a space 15 between them which connects with the opening 17 into which the engine-driven fuel pump discharges. A concentric cone-shaped part 19 is secured at its periphery to the inner vessel 13 and a long tubular portion 21 connects to the opening 23 into which an auxiliary fuel pump discharges. The space 25 between the vessel 13 and cone 19 connects to the outlet opening 27 from which the fuel flows to the carburetor through the pipe 46. The flange of a float housing 29 is held between a cover 31 and an intermediate section 33, leaving a space 35 between the float housing and the intermediate section. Circular rows of small holes 37 and 39 connect the spaces 15, 25, and

35 to each other. The float 48 is guided at the bottom by a tube 41 which fits freely in a hub 43 of the float housing and at the top by a valve needle support 45 which fits freely in a valve seat member 47. The valve needle 49 is resiliently held by a spring 51 extending upward from the bottom of the support 45 which is fastened onto the hub 53 on the upper side of the float, whereby the needle is resiliently seated when the float rises. The sides of the float housing 29 have a 10 plurality of perforations 55.

The auxiliary fuel pump 52 shown to an enlarged scale in Fig. 5 may be connected to either one of the six tanks by a suction pipe 54, the tank selected in the instant case, for illustrative purposes, being tank 6. A discharge pipe 56 extends from the outlet of the auxiliary pump to the bottom of the air separator 44, whereby fuel from the auxiliary pump also passes through the air separator and through pipe 46 to the carburetor 14. The auxiliary pump is also of the type having a relief valve 57 which maintains a given pressure output, the relief valve 57 in the auxiliary pump being set to deliver fuel under a pressure of ten pounds. An electric motor 58 is provided for operating the auxiliary fuel pump.

Since the relief valve 57 is set to return fuel from the high to the low pressure side at ten pounds pressure, and the engine pump 12 puts fuel into the high-pressure side at fifteen pounds pressure, a check valve 59 is provided to prevent fuel returning from the high pressure side through the auxiliary pump 52 to the tank 6.

Check valve 59 shown in detail in Fig. 4 comprises a casing 61 divided into three compartments—63, 65, 67—by two spaced-apart Sylphon diaphragms 69, compartment 65 being open at 87 to the atmosphere, whereby, since the atmospheric pressure acts in opposite directions on the two Sylphons 69, any change in altitude, and its consequent change in atmospheric pressure, does not affect operation of the valve. A valve head 71 has its stem 73 sealed to both diaphragms by nuts 89. Valve head 71 is biased to "open" position by the spring 77 which reacts against a partition 79 extending from the casing 61. Compartment 63 and the space 93 above the relief valve 57 of the auxiliary pump are connected to the pipe 46 by a pipe 91, whereby the valve 59 is closed by the pressure in compartment 63 whenever the discharge pressure of the main pump 12 exceeds the discharge pressure of the auxiliary pump 52 by a predetermined amount, and the spring 99 of the relief valve 57 is assisted in preventing leakage backwardly through the auxiliary pump by the same pressure while compartment 67 is connected by a pipe 93 to the pipe 46 through the air separator 44 and to the outlet 56 of the auxiliary pump when the valve 59 is open.

Connected into the high-pressure side of the two fuel pumps above described, by connecting into the pipe 42, is a fuel-pressure-sensitive electrical switch which may be broadly designated by the numeral 75. Switch 75 comprises a body 60 divided into two compartments by diaphragm 62 which is moved in one direction by the pressure in the pipe 42, but urged in the opposite direction by a spring 64 whereby, in the absence of sufficient pressure in the pipe 42, the spring 64 moves a contact bar 66 into engagement with contacts 68 and 70, thereby keeping switch 75 closed as shown in Fig. 1 until the pressure in pipe 42 is restored. The spring 64 is so proportioned that switch 75 closes upon a drop in pressure in the

pipe 42 to about twelve pounds. A signal lamp 85 is so connected to the switch terminal 70 as to give warning whenever the switch 75 has reached a "closed" position.

A second pressure-sensitive switch, which may be broadly designated by the numeral 81, comprises a body 72 and a contact bar 74 which is adapted to be moved to connect the contacts 76 and 78. Switch 81 may be supported on the engine 10 and is connected to the lubricating oil system by a pipe 83, being responsive to the oil pressure of the engine. The switch 81 is constructed substantially like the switch 75 with respect to the diaphragm and the spring, except that while the application of pressure to the upper surface of the diaphragm of the switch 75 opens it, the application of pressure to the upper surface of the diaphragm of the switch 81 closes it.

20 A main manual switch 80 is provided to connect the battery 82 to the post 84. An additional manually controlled switch 86 connects the switch terminal 70 of the switch 75 to the binding post 88 of the auxiliary pump motor 58. This switch 25 may be used whenever it becomes desirable to stop rotation of the pump motor 58 while the main switch 80 is closed.

An automatic power-operated valve selector 90 (see Figs. 1 and 6) comprises an electric motor 92 which may preferably have an inbuilt speed-reducing gear box of high ratio so that the shaft 94 may operate at greatly reduced speed—that is, the motor 92 may preferably rotate as much as two hundred R. P. M. to one R. P. M. of the shaft 94. A dielectric disk 96 is concentrically supported on the flange 97 of the motor 92, and carries a circular row of twelve electrical contacts, pairs of which are connected to the solenoid-operated valves, contact 1L being connected to the lifting coil of valve 18, and contact 1 being connected to the holding coil of valve 18; contact 2L being connected to the lifting coil of valve 20, and contact 2 being connected to the holding coil of valve 20; etc. A cam 98 is secured to the shaft 94 to rotate in unison therewith. A contact arm 100 is loose on the shaft 94 and insulated therefrom by a dielectric bushing 95 but is caused to rotate with the shaft by means of a plunger 102 which is slidable in a dielectric bushing 103 in 50 the end of the arm 100 and has its free end extending into one of the six notches 104. A knob 105 is provided, the knob and the arm 100 both being fast on the bushing 95, whereby the contact arm 100 may be manually rotated in advance 55 of the slow rotation of cam 98 when so desired. A spring 106 maintains the plunger 102 seated in whichever notch it happens to engage.

On the outside of cam 98 are a series of six cam lobes 108 equally spaced around its periphery. 60 A dielectric plunger 110 is carried on a metal arm 112 which is hinged at 114 to the dielectric disk 96, the free end of this arm being adapted to engage an extension of the binding post 116 of the motor 92. A coil spring 118 urges the arm 112 65 toward engagement with the binding post extension. The point of contact between the arm 112 and the extension of the binding post 116 serves as a switch which may be hereinafter referred to as the switch 120. Electrical conductors connect the post 84 to the terminal 68 of switch 75, the terminal 70 to its signal light 85, the terminal 70 to the terminal 76, the terminal 78 to the binding post 116, the terminal 70 through the switch 86 to the binding post 88, and the post 84 to the 70 75 arm 112 and the contact arm 100.

The operation of the mechanism is as follows: If the engine is at rest and no fuel pumps are in operation, the reduced pressure in the body 60 of the switch 75 will have permitted the switch to be closed as shown; while absence of oil pressure in the engine 10 will have permitted the switch 81 to be opened as shown. In order to start the engine, the main switch 80 and the manual switch 86 should now be closed. This will supply current to the binding post 88 of the auxiliary pump motor 58. Rotation of the auxiliary pump 52 will now build up a pressure of ten pounds in the carburetor 14, which is enough to start the engine. The building up of the pressure in this manner should be accomplished before there is any attempt to start the engine. The ten-pound pressure supplied to the carburetor 14 will not, however, operate the switch 75 to "open" position, inasmuch as this switch is set to open at twelve pounds. As soon, however, as the engine starts, the pump 12, which is set to deliver fuel at fifteen pounds pressure and which is driven by the engine, will operate the switch 75 to "open" position, while the oil pressure built up by the engine will operate the switch 81 to its "closed" position. As soon as this occurs, current will be cut off from the auxiliary pump motor 58, and the duty of supplying a fifteen-pound pressure to the carburetor 14 will be assumed by the pump 12, the check valve 59 becoming operative to prevent fluid from the pump 12 being pumped in reverse direction through the relief valve 57 of the auxiliary pump 52, and the relief valve 57 being reinforced against leakage by virtue of the fifteen-pound pressure being applied in the space above the relief valve to hold it closed.

Thus far no electric current has as yet been delivered to the binding post 116 of the valve selector motor 92, inasmuch as the switch 75 and the switch 81 have not thus far been closed at the same time; neither has current been delivered to the binding post 116 through the arm 112, since this occurs only when the spring 118 effects contact of the arm with the binding post, which may not occur until the lobe 108 of the cam moves from under the lobe 110 of the arm. The contact arm 100, therefore, up to this time, has maintained the valve 18 in its "open" position and will continue to so maintain it until current is in some manner supplied to the binding post 116.

When the engine has been in operation for a sufficient time to empty the tank 1, the pump 12 will momentarily draw air from the empty tank 1 and pump it into the pipe 42, which will instantly cause the pressure in the discharge pipe 42 to drop. When it has dropped to as little as twelve pounds, which will be almost instantly, the switch 75 will close, while the previously closed switch 81 remains closed, the air drawn in by pump 12 passing out through the air separator 44. When both switches 75 and 81 are closed, current will flow to the binding post 116, and the selector motor 92 will begin rotating the cam 98 clockwise, carrying the contact arm 100 with it. As soon as the cam 98 rotates slightly, the lobe 108 moves from under the lobe 110 and the spring 118 closes the switch 120, after which current will be supplied to the binding post 116 directly from the post 84 until the next succeeding lobe 108 moves under the lobe 110, thereby opening the switch 120 and stopping the arm 100 at the desired place.

The above arrangement is highly desirable, for while the arm 100 would continue rotation as long as current was being supplied to the motor

92 from the ignition post through both switches 75 and 81, the arm could readily stop rotating before it had reached a proper position for holding open the valve 20 of tank 2, since the fuel pump 12 might readily have built up a pressure of twelve pounds and opened the switch 75 in advance of a complete movement of the arm 100 through 60 degrees to its next succeeding position. With the arrangement shown, when a tank from which fuel is being pumped becomes empty and air passes through the pump 12, resulting in a drop in pressure on the diaphragm 62, and the valve 75 thereby closes and starts rotation of the arm 100, rotation may not cease until the arm has traveled through one-sixth of a revolution, even though pump 12 may build up sufficient pressure to open the switch 75 before the one-sixth revolution has been completed. It should be kept in mind also that the auxiliary pump 52 continues to supply fuel under a pressure of ten pounds up to the instant that the engine-driven pump 12 builds up its pressure to twelve pounds and opens the switch 75, which insures a satisfactory fuel pressure during the entire time that a change-over from an empty to a full tank takes place.

When the next succeeding lobe 108 has raised the lobe 110 and opened the switch 120, the arm 100 will have passed the contact 2L by which the valve 20 was opened and will now be resting only on the contact 2 by which the valve 20 will be held open. The width of the arm 100 and the size and spacing of the contacts, however, should be such that the arm engages the contact 2 slightly before it leaves the contact 2L, for otherwise the valve would close as soon as the arm left the contact 2L. When change in connection has thus been made between an empty tank 1 and a full tank 2, no further changes will take place until tank 2 becomes empty. If, however, tank 2 when thus connected was found to be already empty, the selector merely passes over it, since air drawn from empty tank 2 and transferred to pipe 42 would close the switch 75 and move the arm 100 forward to connect the tank 3. Thus the automatic selector will search the entire series of tanks and will not stop until a full one is found, the auxiliary pump meanwhile maintaining a satisfactory fuel pressure until a full tank is found. Such an arrangement is desirable because it may sometimes happen, particularly where the system is used on war craft, that one of the tanks will have been punctured and the fuel lost, in which case it becomes necessary that the selector operate to pass such tank and connect the system to one that is full. As an added measure of safety, I may provide a multiple hand-operated fuel valve 122 by which any one of the tanks may be connected to the pump 12 should automatic operation of the selector valve fail. The need for using this manual valve would appear upon an extended signal from the light 85.

I claim:

1. The combination, in an aircraft fuel system, of an engine, a main fuel pump driven by said engine, a plurality of fuel tanks each connected to the suction side of said pump, an electromagnetically operated valve interposed in each of the lines which connect a tank to the pump, a solenoid for holding the valve open, a carburetor connected to the discharge side of said pump, an auxiliary fuel pump having its suction side connected to one of said tanks independently of the electromagnetically operated valve and having its discharge line connected to the discharge side

of said main pump, a check valve in said discharge line biased to prevent flow from the discharge side of the main fuel pump to the discharge side of the auxiliary fuel pump, an electric motor for driving said auxiliary fuel pump, an electric current source, a switch for connecting said electric motor to said source, a pressure operated means connected to the discharge side of said main fuel pump for holding said switch open by said discharge pressure, a rotatable switch having circumferentially spaced insulated current supplying contacts for directing current to the coils of the electromagnetically operated valves, an electric motor for rotating said rotatable switch, a cam rotatable by said motor, said cam having a series of lobes and a series of detent notches, each corresponding to the number of electrically operated valves, a cam operated switch, successively operable to open position by each of said lobes upon rotation of said cam, a current supplying arm rotatable about the axis of said cam, a detent member carried by said arm for resiliently engaging in any selected one of said detent notches, said notches and said lobes being so spaced on said cam that when the arm engages a valve holding solenoid contact, the cam operated switch is open, electrically conductive means for connecting the current source in parallel through the fuel pressure operated switch and through the cam operated switch to the rotatable switch electric motor, electrically conductive means for connecting the current source to the arm of the rotatable switch, and electrically conductive means for connecting the current source through the fuel pressure operated switch to the auxiliary pump motor.

2. The combination, in an aircraft fuel system, of a plurality of main fuel supply tanks, a main engine driven fuel pump, valves operable to connect the suction side of said pump to either of said main fuel supply tanks, a reserve fuel supply container, an electric motor driven auxiliary fuel pump having its suction side connected to said reserve fuel supply container, a fuel receiving means, the discharge side of both said pumps being connected to said fuel receiving means, and the main fuel pump being adapted to deliver fuel at a higher pressure than the auxiliary fuel pump, a check valve adapted to prevent flow from the discharge side of said main fuel pump to the discharge side of said auxiliary fuel pump, a pressure responsive switch associated with the main fuel pump, adapted, upon a predetermined drop in pressure at the discharge side of the main fuel pump, due to a tank to which its suction side is connected being empty, to close and direct an electric current to operate said electric motor driven auxiliary fuel pump, and electromagnetic valve operating means operative by said switch upon closing to close the valve of the empty tank and open the valve of the next full tank, whereby said main fuel pump may provide said predetermined pressure to open said pressure operated switch to stop said electric motor driven auxiliary pump.

3. The combination, in an aircraft fuel system, of a plurality of main fuel-supply receptacles, a main fuel pump having its suction side connected to either of said receptacles, a reserve fuel-supply container, an electric motor driven auxiliary fuel pump having its suction side connected to said container, a fuel receiving means, the discharge side of both said pumps being connected to said fuel receiving means, and the main fuel

pump being adapted to deliver fuel at a higher pressure than the auxiliary fuel pump, a check valve adapted to prevent flow from the discharge side of said main fuel pump to the discharge side of said auxiliary fuel pump, a pressure responsive switch associated with the main fuel pump, adapted, upon a predetermined drop in pressure at the discharge side of the main fuel pump, due to a receptacle to which its suction side is connected being empty, to close and direct an electric current to operate said electric motor driven auxiliary fuel pump, and electromagnetic means operative by said switch, upon closing, to disconnect the suction side of the main fuel pump from the empty receptacle and connect it to a full receptacle, whereby said main fuel pump may provide said predetermined pressure to open said pressure operated switch to stop said electric motor driven auxiliary pump.

20 4. The combination, in an aircraft fuel system, of a main fuel supply receptacle, a main fuel pump having its suction side connected to said main fuel supply receptacle, a reserve fuel supply container, an auxiliary fuel pump having its suction side connected to said reserve fuel supply container, a fuel receiving means, the discharge side of both said pumps being connected to said fuel receiving means, and a fuel pressure responsive means associated with the main fuel pump, adapted, upon a predetermined drop in pressure at the discharge side of the main fuel pump to operate said auxiliary fuel pump.

25 5. The combination, in an aircraft fuel system, of a main fuel supply receptacle, a main fuel pump having its suction side connected to said main fuel supply receptacle, a reserve fuel supply container, an auxiliary fuel pump having its suction side connected to said reserve fuel supply container, a fuel receiving means, the discharge side of both said pumps being connected to said fuel receiving means, and a pressure responsive means associated with the main fuel pump, adapted, upon a drop in pressure at the discharge side of the main fuel pump to a pressure slightly above the discharge pressure capacity of the auxiliary fuel pump to operate said auxiliary fuel pump, whereby restoration of the discharge pressure of the main fuel pump is required to stop the auxiliary fuel pump.

30 6. The combination, in an aircraft fuel system, of a main fuel supply receptacle, a main fuel pump having its suction side connected to said main fuel supply receptacle, a reserve fuel supply container, an auxiliary fuel pump having its suction side connected to said reserve fuel supply container, a fuel receiving means, the discharge side of both said pumps being connected to said fuel receiving means, each pump being adapted to maintain a predetermined discharge pressure, the predetermined discharge pressure of the main pump being higher than that of the auxiliary pump, and a pressure responsive means associated with the main fuel pump, adapted, upon a predetermined drop at the discharge side of the main fuel pump to a pressure between the discharge pressures of the two said pumps to operate said auxiliary fuel pump, whereby restoration of the main pump to its predetermined pressure capacity will stop operation of the auxiliary pump.

35 7. The combination, in an aircraft fuel system, of an engine, a main fuel supply receptacle, an engine driven fuel pump having its suction side connected to said main fuel supply receptacle, 40 a reserve fuel supply container, an electrically

driven fuel pump having its suction side connected to said reserve fuel supply container, a fuel receiving means, the discharge side of both said pumps being connected to said fuel receiving means, each pump being adapted to maintain a predetermined discharge pressure, the predetermined discharge pressure of the engine driven pump being higher than that of the electrically driven pump, and a pressure responsive electric switch associated with the main fuel pump, adapted, upon a predetermined drop at the discharge side of the main fuel pump to a pressure between the discharge pressures of the two said pumps to operate said auxiliary fuel pump, whereby restoration of the engine driven pump to its predetermined pressure capacity will stop operation of the electrically driven pump.

8. The combination, in an aircraft fuel system, of an engine, a main fuel supply receptacle, an engine driven fuel pump having its suction side connected to said main fuel supply receptacle, a reserve fuel supply container, an electrically driven fuel pump having its suction side connected to said reserve fuel supply container, a fuel receiving means, the discharge side of both said pumps being connected to said fuel receiving means, the engine driven pump being arranged to maintain a predetermined discharge pressure and the electrically driven pump being arranged to maintain a lesser discharge pressure than the engine driven pump, a pressure responsive electric switch connected to the discharge side of the main fuel pump, adapted, upon a drop at the discharge side of the main fuel pump to a pressure

which is between the discharge pressures of the two pumps to operate said electrically driven pump, and a check valve interposed between the discharge sides of the two pumps biased to prevent flow from the discharge side of the engine driven pump to the discharge side of the electrically driven pump.

9. The combination, in an aircraft fuel system, of an engine, a plurality of main fuel supply receptacles, an engine driven pump having its suction side connected to either of said main fuel supply receptacles, a reserve fuel supply container, an electrically driven pump having its suction side connected to said reserve fuel supply container, a fuel receiving means, the discharge sides of both pumps being connected to said fuel receiving means, the engine driven pump being arranged to maintain a given discharge pressure and the electrically driven pump being arranged to maintain a lower discharge pressure than the engine driven pump, a pressure responsive electric switch connected to the discharge side of the engine driven pump, adapted upon a drop at the discharge side of the engine driven pump, to a pressure which is between the discharge pressures of the two said pumps, to operate said electrically driven pump and electromagnetic means operative coincidentally with said pressure responsive electric switch to disconnect one main fuel supply receptacle from the suction side of the engine driven pump and connect another main fuel supply receptacle thereto.

DAVID SAMIRAN.
